J. IWANICKI

TOOTHPICK DISTRIBUTOR

Filed Aug. 11, 1927

UNITED STATES PATENT OFFICE.

JOSEPH IWANICKI, OF DETROIT, MICHIGAN.

TOOTHPICK DISTRIBUTOR.

Application filed August 11, 1927. Serial No. 212,167.

This invention relates to improvements in tooth-pick distributors.

At the present time toothpicks are frequently placed in open receptacles with the result that they are exposed to the dust and dirt. Moreover they are often so placed that in order to pick up one toothpick a person's fingers come in contact with several other toothpicks he has no intention of taking. It is an object of this invention to provide a toothpick distributor from which toothpicks are distributed one at a time so that those remaining therein are protected from dust, dirt and handling.

Another object of the invention is to provide a toothpick distributor which can be cheaply manufactured, which is simple to operate, and which automatically raises a toothpick into an inclined position so that it may be readily taken after the toothpick has been brought into discharging position by operating a handle.

With these and other objects in view which will be pointed out as the specification proceeds, the invention is hereinafter more fully described with the aid of the accompanying drawings, in which—

Figure 1 illustrates a sectional elevation of the invention.

Figure 2 is a section on the line 2—2 of Figure 1.

Figure 3 is a section on the line 3—3 of Figure 2.

Figure 4 is a section on the line 4—4 of Figure 3, and

Figure 5 shows an enlarged detail.

Referring to the drawings, 1 designates a casing having a container 2 in the upper part thereof which is usually enclosed by a cover 3; in the present instance the latter is shown hinged at 4. The underside 5 of the container is downwardly inclined from both front and rear towards a transverse slot 6, and this underside 5 is also preferably corrugated transversely so as to tend to hold the toothpicks 7 in such position that they will lie substantially parallel with the said slot.

Under the slot 6 and substantially parallel with it a shaft 8 is located which is rotatably supported in the sides of the casing 1. Fixed on this shaft are a plurality of discs 9 having opposed peripheral notches 10. These discs and this shaft are so positioned that as they rotate each opposed set of notches in turn passes in propinquity to the underside

of the slot 6, and the upper front portions of the said discs rotate in proximity to a portion 11 of the casing which is positioned that once a toothpick has dropped into a set of notches it cannot become disengaged from them while passing the said casing portion.

Revolvably supported in the casing is a second shaft 20 substantially parallel with and below the first named shaft 8. This second shaft also has discs 21 fixed thereon which have opposed peripheral notches 22 therein. The discs 21 are preferably placed substantially in line with the discs 9 so that the downwardly inclined portions of the latter discs pass in proximity to the upwardly inclined portions of the discs 21.

A forwardly extending portion 12 of the casing has a transverse discharge opening 13 therethrough, and within the casing and along the front margin of the said opening 13 is a depending rest 15 which terminates in proximity to the periphery of the discs 21; and along the rear margin of the said opening 13 is a guide member 16 which extends downwardly almost to the peripheries of the discs 21, has a rearwardly curved portion 17 which is flexed over portion of the peripheries of the said discs, and terminates in an upwardly curved portion 18 which conforms to the curvature of a portion of the discs 9 and is spaced a short distance from their peripheries. On the rear wall of the casing 1 a member 19 is secured which is provided with an upwardly flexed guide 19^a that extends between the discs 9.

When the discs 9 and 21 are turned, by means hereinafter set forth, the toothpicks 7 drop one at a time into the notches 10 as the latter pass the slot 6, from the said notches 10 between the upwardly curved portion 18 and the guide 19^a onto the discs 21 and then into the notches 22. The rearwardly curved portion 17 of the guide member 16 prevents toothpicks from riding on the discs 21 unless in position in the notches 22, and once the toothpicks are in engagement in the latter notches they cannot become disengaged therefrom until they arrive under the opening 13.

On one end of the shafts 8 and 20 sprocket wheels 24 and 25 are secured, which latter are connected by a chain 26; and on the shaft 20 a ratchet wheel 27 is also secured.

Within the casing and on the front side thereof is a bracket 28 having a link 29 piv-

totally mounted thereon, and to the outer end of the latter a dog 30, adapted to engage the teeth of the ratchet wheel 27, is pivotally secured. An operating rod 32 extends through an opening 32^a in the top of the casing 1, is pivotally connected intermediately of its length to the link 29 as by a pin 38, and at its lower end this rod has a slotted opening 34 therethrough. Portions 38 and 38^a of the casing support a spindle 35 which has a forwardly flexed portion 36 the extremity of which is inturned to take into the slotted opening 34 in the lower end of the operating rod 32. Fixed on the spindle 35 is an arm 39 which has a slotted hole 40 through its outer end. Slidably mounted in clips 41 secured to one side of the casing is a vertical slide 42 the lower end of which is pivotally fastened to the arm 39 as by a bolt 43 which passes through the slide and also through the said slotted hole 40. On the upper end of the slide is a holding member 44 which has a vertically inclined face adjacent to one of the discs 21.

25 The link 29 is normally held in the position shown in Figure 1 by a spring 45, and the upper end of the operating rod 32 is threaded at 46 for a stop 47 so that by adjusting the latter the distance between the stop 30 and the top of the casing, when the operating rod is in normal (up) position, may be regulated. In this way the travel of the operating rod may be set after the machine is made so that each downstroke will advance the 35 discs the desired amount to bring the notches 10 and 22 under the slot 6 and discharge opening 13 respectively.

The operation of the distributor is briefly as follows:

40 When the operating rod 32 is depressed the dog 30 turns the ratchet wheel 27, and the shafts 20 and 8, the latter through the sprocket and chain drive 24, 25 and 26. This causes the discs 9 and 21 to turn. Each time 45 a set of notches 10 pass under the slot 6 they carry a toothpick around and drop it between the plate 18 and the guide 19^a onto the periphery of the discs 21 where it falls into the next set of notches 22 and is carried under the discharge opening 13. Moreover on each 50 down stroke of the rod 32 another set of notches 22 are brought into position under the said opening 13. Each time the spring 45 returns the rod 32 from down to normal (up) 55 position the slide 42 is moved down so that its upper portion strikes one end of the toothpick under the opening 13 and raises it partly through the opening into the inclined position shown in Figure 3 so that it may be readily taken hold of.

60 While in the foregoing the preferred embodiment of the invention has been described and shown, it is understood that the construction is subject to such modifications as fall 65 within the scope of the appended claims.

What I claim as my invention and desire to secure by Letters Patent is:

1. In a toothpick distributor, the combination of a casing, a container in said casing, said casing having a discharge opening there-through, means for conveying toothpicks from said container to the underside of said opening, a slide having an inclined face at its upper end, an operating rod for actuating said conveying means, a spring for returning said operating rod to normal position, and means connected to said operating rod adapted to move said slide downwards so that its inclined face presses down on one end of a toothpick under said discharge opening and moves the latter into an inclined position projecting partly through said opening as said rod is returned to normal position.

2. In a toothpick distributor, the combination of a casing having a discharge opening therein, a container having a slot in its underside, shafts revolvably mounted in said casing, discs on said shafts, said discs having opposed peripheral notches therein, the discs on one shaft being adapted to rotate under said slot so that toothpicks dropped through said slot fall into one set of said peripheral notches, means for preventing said toothpicks passing out of said slot except when in engagement with one set of peripheral notches, means adapted to guide said toothpicks as they drop from the notches in the discs under said slot as the latter discs turn, said latter means causing said toothpicks to engage one set of notches in said other discs, said other discs being adapted to deliver said toothpicks under said discharge opening, a movable operating rod, means connected to said operating rod for rotating said discs, means for returning said operating rod to normal position, and means adapted to raise a portion of a toothpick delivered under said discharge opening into an inclined position extending partly through said opening as said operating rod is returned to normal position.

3. In a toothpick distributor, the combination of a casing having a discharge opening therein, a container adapted to hold toothpicks in said casing having a slot in its underside, shafts revolvably mounted in said casing, discs on each of said shafts having opposed peripheral notches therein, the discs on one shaft being adapted to rotate under said container slot adjacent to the underside of the container so that a toothpick may fall into and across each set of notches as said discs turn, means for preventing toothpicks from becoming disengaged from said notches until said discs have turned a predetermined distance, means adapted to guide each toothpick as it falls from said notches so that it drops onto the other discs on the other shaft and is engaged by notches in said other discs, said other discs being adapted to deliver said toothpicks under said discharge opening, an

operating rod, by which said shafts are turned, and means connected to said operating rod for delivering a toothpick through said discharge opening.

- 5 4. In a toothpick distributor, the combination of a casing having a discharge opening therein, a container in said casing adapted to hold toothpicks and having a slot in its underside, discs revolvably mounted under said 10 container, means on the periphery of said discs for receiving said toothpicks one at a time from said slot, other discs onto which said toothpicks are adapted to fall from said first named discs, said other discs being 15 adapted to deliver said toothpicks under said discharge opening, means for turning said discs, and means for raising said toothpicks

so that they project through said discharge opening.

5. In a toothpick distributor, the combination of a casing with a discharge opening therein, a container adapted to hold toothpicks in said casing having a slot in its underside, discs revolvably mounted in said casing, means on said discs for delivering one toothpick at a time under said discharge opening, and a slide adjacent to one of said discs adapted to bear against a toothpick in proximity to one of its ends and raise the opposite end of the toothpick through said discharge 20 25 30 opening utilizing said adjacent disc as a fulcrum, means for moving said discs, and means for moving said slide.

JOSEPH IWANICKI.
